CLAIM

The ornamental design for a razor cartridge shaving aid assembly, as shown and described.

DESCRIPTION

FIG. 1 is top view of an embodiment of an ornamental design for a razor cartridge shaving aid assembly according to the present invention;

FIG. 2 is a bottom view thereof;

FIG. 3 is a right view thereof;

FIG. 4 is a left view thereof;

FIG. 5 is a front side view thereof;

FIG. 6 is a bottom view thereof; and,

FIG. 7 is a front perspective view thereof.

The broken lines illustrate a portion of the razor cartridge shaving aid assembly and form no part of the claimed design.
